BUILDING CONSTRUCTION

Eldridge T. Spence, San Francisco, Calif., assignor of one-third to Kenneth H. Dyer, Berkeley, Calif.

Application July 17, 1939, Serial No. 284,871

3 Claims. (Cl. 20—2)

The present invention relates to improvements in building construction and has particular reference to the quick and economic construction of relatively simple buildings by means of pre-fabricated units.

One of the objects of the present invention is to provide a wall unit of considerable area that may be pre-fabricated and shipped from the factory to the location of the building to be erected and may be easily and simply applied by the person constructing the house, the unit being comparatively light in weight and of sufficient area that relatively few units are necessary for the completion of the building.

Another object of my invention is to provide a wall unit of the character described that is substantially self-sustaining and does not need any studdings for supporting the same.

It is further proposed to provide means for holding the unit in vertical position, such means working on the cantilever principle and enabling the wall to take lateral stresses as well as vertical stresses, without requiring any bracing means except such as are inherent in the construction of any building having intersecting walls.

A still further object of my invention is to provide means for joining different units in such a manner that the building structure is not weakened at the joints and is as leak-proof at the joints as in other places, while at the same time, the appearance of the joints when completed does not distinguish from the remainder of the wall structure.

Further objects and advantages of my invention will appear as the specification proceeds and the novel features of the same will be set forth in the claims hereto appended.

The preferred form of my invention is illustrated in the accompanying drawing forming part of this application, in which:

Figure 1 shows a vertical section through a simple building structure made in accordance with my invention;

Figure 2, a horizontal section through a corner of the building, and

Figure 3, a perspective detail view of one of the wall units used in my invention.

While I have shown only the preferred form of my invention, I wish to have it understood that various changes or modifications may be made within the scope of the claims hereto attached without departing from the spirit of the invention. Particularly, it should be pointed out that my building structure unit may be as suc-

cessfully employed in other structures than buildings, such as fences, bill boards and the like.

Referring to the drawing in detail, and particularly to Figure 3, it will be seen that my building unit 1 comprises a panel 2, a superimposed insulating paper 2', a plurality of boards 3 arranged on the panel lengthwise and a number of battens 4 covering the cracks or joints 10 between the boards.

The panel is preferably made of ply-wood and is of a length corresponding to the wall height of the building to be erected. Its width is preferably 48 inches, although, of course, the width 15 may be changed to suit particular conditions.

It should be understood, however, that the word panel, as used in this specification, is meant to describe a flat building unit of considerable width, preferably at least three feet, 20 and relatively thin, preferably about one-fourth or less of the thickness of the boards hereinafter mentioned. Such panels are of standard type in building construction and are usually known as three-ply panels.

25 The boards are preferably of the size of 1 by 12 inches so that four boards are required to cover one panel. Boards which are sold on the market as 1 by 12's usually are a little less in width than 12 inches, say about one quarter of an inch, so that the total width of the four boards is about one inch less than that of the panel.

The boards are placed on the panel in such a manner that at each side edge the panel projects 35 about $\frac{1}{2}$ an inch beyond the outer board, as shown at 5. These margins are used in the assembling of the structure to bring about a joint that resembles the joints between the individual boards so that no difference in appearance is discernible between the different points.

For erecting the building, a suitable substructure is used, such as cement foundation indicated at 6, or a foundation of any other type desired which has a flat and level upper surface.

45 A so-called plate 7 of conventional type is placed on the foundation, the plate corresponding in location to the outline of the building to be erected.

Floor joists 8 are stretched across the building in the usual manner so that their ends rest on 50 oppositely disposed plates. The ends of the floor joists are joined by means of a transversely disposed board or plank 9 of the same height as the joists and the joists at the extreme ends of the building are made to rest on the end plates 55 in the same manner, so that the boards 9 and

the end joists form a complete and continuous closure, leaving about one-half of the width of the respective plates to project beyond the floor joist area, as indicated at 10.

The building units are placed in upright position and in adjacent relation on the projecting portion of the plate so as to be supported thereon against vertical stresses, the panels facing inwardly, and their lower ends are nailed to the boards 9 or the end joists, the nails being made to pass through the boards 3, the insulating paper and the panels into the supporting boards.

Each of the building units is thus self-sustaining and is held, cantilever-style, against lateral stresses, without any further supporting means. Where two units are joined, as at 11 in Figure 2, the two panels are made to contact, but the outer boards will have about one inch clearance, due to the fact that the panel projects about $\frac{1}{2}$ an inch beyond the marginal board.

This clearance is taken up by a wooden filler 11', which may be one by one or three quarters by three quarters inches, depending upon the width of the clearance, a piece of insulating paper 12 being interposed between the three contacting sides of the filler and the walls forming the clearance. Finally a batten 13 is placed over the filler and adjacent parts of the adjacent boards, the batten being of the same width and thickness as the other battens used to cover the cracks between the boards of each building unit.

The corner construction is also illustrated in Figure 2. The corner building units are made to contact at the inner panel edges, as at 14, and may be secured to a corner piece 15. Two fillers 16 are used to cover the projecting margins of the panels and to contact, as at 17, and two battens 13' are employed to cover the joint, one of the battens overlapping the edge of the other, as at 18.

For roof construction, a plate 24 is placed on top of the assembled wall structure, with a portion overhanging outwardly, as at 19 and another portion overhanging inwardly as at 20. A suitable moulding 21 may be placed in the corner as shown. Cords 22 and rafters 23 are then assembled in the conventional manner and mounted on the plates. The rafters may be covered with sheathing and shingles or any other suitable roofing material.

It will be noted that this type of building construction offers many advantages.

The building units lend themselves readily to prefabrication with standard materials. No matter what size panels of ply-wood are used, whether 3, 4, 8, 10 or 12 feet in width, and what sizes of boards are used, whether 6, 8, 10 or 12 inches in width, the general rule prevails that the aggregate width of standard size boards used will be somewhat less than the width of the panel, if the commercial overall dimensions are made to agree.

This is true because the actual width of the boards is somewhat less than the indicated width while in ply-wood panels the actual width corresponds to the indicated width.

Thus it is always possible by suitable selection of boards and panels and suitable placing of the boards on the panels to cause the latter to project beyond the outer boards by about one-half of an inch, thus forming a continuous surface on the inner or panel side of the structure while providing filler grooves on the outer or board side adapted to be sealed by the one inch or

three-quarter inch filler strips surrounded by weather proof paper or cloth.

Both sides of the wall lend themselves to finishing by application of suitable decorative features.

The corners of the building may be finished by use of the same material as is used at the joints in the flat faces of the wall.

Due to the possible omission of the studdings, the weight and material used is considerably less than in conventional structure using the studding, which makes for economy in construction and cheapness in cost.

Due to fabrication of large units, light in weight, the cost of labor in assembling the building is reduced considerably and the time consumed in erecting the building is cut down and also less skilled aid is necessary in constructing the same.

20 The cantilever action is of particular importance. Each wall building unit stands by itself, resting firmly on the plate against vertical loads and being secured at its lower end to the floor joists assembly to stand upright against wind pressure and lateral stresses, such as occasioned by earthquakes. The number of nails or hardware used for securing the panels is negligible as compared with conventional construction.

25 The upper ends of the upright panels are joined by the top plates which serve in distributing loads, lateral as well as vertical. And finally the upper ends of opposing side walls are joined by the ceiling or roof construction so that the opposite wall cooperates with the near wall in resisting wind pressures or lateral loads brought to bear on the latter.

30 The top plate also serves to distribute lateral pressures where some of the panels are not in cantilever action on account of being non-continuous, as, for instance, being interrupted by window and door construction.

I claim:

1. In building construction, a unitary floor joist assembly having opposing vertical faces, pre-fabricated building units comprising relatively thin and wide ply-wood panels of wall height and a substantially continuous series of upright boards of less width and greater thickness secured to the outside thereof from the bottom up so as to take the bulk of lateral stresses, the said building units being arranged with their lower ends adjacent the vertical faces of the floor joist assembly, and means passing through the boards and the panels into the floor joist assembly for securing the lower ends of the building units to the vertical faces of the floor joist assembly, whereby each unit is independently supported against lateral stresses and in the absence of supporting frame members.

2. In building construction, a horizontal foundation, a unitary floor joist assembly resting thereon and having opposing vertical faces, pre-fabricated building units comprising relatively thin and wide ply-wood panels of wall height and a substantially continuous series of upright boards of less width and greater thickness secured to the outside thereof from the bottom up so as to take the bulk of lateral stresses, the said building units being arranged with their lower ends resting on the foundation and disposed adjacent the vertical faces of the floor joist assembly, and means passing through the boards and the panels into the floor joist assembly for securing the lower ends of the building units to the vertical faces of the floor joist assembly, whereby each unit is

independently supported against lateral stresses and in the absence of supporting frame members.

3. In building construction, a horizontal foundation, a unitary floor joist assembly resting thereon and having opposing vertical faces, pre-fabricated building units comprising relatively thin and wide panels of wall height and a substantially continuous series of upright boards of less width and greater thickness secured to the outside thereof from the bottom up so as to take the bulk of lateral stresses, the said building units being arranged with their lower ends resting on

the foundation and disposed adjacent the vertical faces of the floor joist assembly, means passing through the boards and the panels into the floor joist assembly for securing the lower ends of the building units to the vertical faces of the floor joist assembly, whereby each unit is independently supported against lateral stresses and in the absence of supporting frame members, and horizontal cords interconnecting the upper ends of opposing panels.

ELDRIDGE T. SPENCER.
